UNITED STATES PATENT OFFICE.

SAMUEL GRAHAM, OF LEBECK, MISSOURI.

DESIGN FOR A SPIKE.

SPECIFICATION forming part of Design No. 32,958, dated July 17, 1900.

Application filed May 28, 1900. Serial No. 18,165. Term of patent 14 years.

To all whom it may concern:

Be it known that I, SAMUEL GRAHAM, a citizen of the United States, residing at Lebeck, in the county of Cedar and State of Missouri, have invented and produced a new and original Design for Spikes, of which the following is a specification.

My new and original design has for its object to give a novel shape to the body of a spike.

Figure 1 is an elevation of a railroad-spike made according to my design, and Fig. 2 is a cross-sectional view taken on the line 2 2 of Fig. 1.

In the drawings, 1 indicates the head of the spike, and 2 the body thereof. The body is chisel-pointed, as represented at 3, and has its upper portion—that is, the portion toward the head—substantially square in cross-section. The four corners of the lower portion of the body of the spike are cut away, so as to form a series of flat triangular-shaped faces 4 between the side faces 6 of the spike. These cut-away portions terminate at the top of the chisel-point of the spike, where there are

formed a series of four shoulders or shelves 5. The cut by which the face 4 is formed is progressively deeper from the top to the bottom—that is, the face 4 is at an angle to the axis of the spike, the plane of each face approaching the axis from the top toward the bottom.

As viewed from a position directly in front of either face 6 of the spike, such face will be seen to taper from where the faces 4 begin at about the middle of the spike to the shoulders 5 at the head of the chisel-point, at which latter place the face 6 is very narrow.

What I claim, and desire to secure by Letters Patent, is—

The design for a spike, substantially as herein shown and described.

In testimony whereof I have signed my name to this specification in the presence of two witnesses.

SAMUEL GRAHAM.
